UNITED STATES PATENT OFFICE.

ALLEN D. LINN AND LOUIS GOHLKE, OF GRAND RAPIDS, MICHIGAN,
ASSIGNORS TO THE GRAND RAPIDS SCHOOL FURNITURE COMPANY,
OF SAME PLACE.

DESIGN FOR A DESK.

SPECIFICATION forming part of Design No. 24,803, dated October 29, 1895.

Application filed September 11, 1895. Serial No. 562,216. Term of patent 7 years.

To all whom it may concern:

Be it known that we, ALLEN D. LINN and LOUIS GOHLKE, citizens of the United States, residing at Grand Rapids, in the county of Kent and State of Michigan, have invented and produced a new and original Design for Desks, of which the following is a specification.

In the accompanying drawings, Figure 1 is an elevation of the desk-box. Fig. 2 is a plan view, and Fig. 3 is a section.

The leading feature of the design consists in the configuration of the school desk-top.

In the drawings the side pieces are shown at *a*, the bottom at *b*, and the top at *c*. The pieces *a* are plain except at their lower edges, where they are provided with a bead *d*. At

each corner is arranged a block *e*, having the configuration shown and appearing to be a continuation of the side pieces. These blocks ²⁰ have a bead *d'* at their lower ends, which forms a continuation of the beads *d* of the side pieces. The top of the box has rounded corners, as shown in Fig. 2.

What we claim is—

The design for a school desk top herein shown and described.

In testimony whereof we affix our signatures in presence of two witnesses.

ALLEN D. LINN.
L. GOHLKE.
